UNITED STATES PATENT OFFICE.

ALBERT M. PRICE, OF CHICAGO, ILLINOIS, ASSIGNOR TO WILLIAM H. FAUBER, OF SAME PLACE.

DESIGN FOR A CRANK-ARM AND SPROCKET-WHEEL FLANGE FOR VELOCIPEDES.

SPECIFICATION forming part of Design No. 32,349, dated March 13, 1900.

Application filed February 12, 1900. Serial No. 5,030. Term of patent 7 years.

To all whom it may concern:

Be it known that I, ALBERT M. PRICE, a citizen of the United States, residing at Chicago, in the county of Cook and State of Illinois, 5 have invented and produced a new and original Design for a Crank-Arm and Sprocket-Wheel Flange for Velocipedes, of which the following is a specification, reference being had to the accompanying drawings, forming 10 part hereof.

In the drawings, Figure 1 is a side elevation of a crank-arm and sprocket-wheel flange embodying my design. Fig. 2 is a rear elevation thereof.

15 The leading or characteristic features of a crank-arm and sprocket-wheel flange made in accordance with my design are as follows: The crank-arm is smaller at its outer than at its inner end, is rectangular in cross-section 20 at its outer end and at a point closely adjacent to the head thereof, to which the pedal-shaft is attached, and is of lozenge or diamond shape at its inner end or that adjacent to the crank-shaft. The sprocket-wheel flange is 25 circular and provided with a plane outer face adjacent to the crank-arm, which extends to a plane coincident with the plane of the inner surface of the adjacent part of the crank-arm. Said flange is provided with a cylindric peripheral surface, at the inner margin 30 of which is located a marginal radial flange, which forms, with the peripheral surface of the main flange, a marginal annular rabbet. From the outer end of the arm the four plane 35 faces thereof, located at the front, rear, and sides of the arm, taper gradually toward the crank-shaft end of the arm, where the two margins bounding each of said surfaces are brought together, or nearly so. The oblique

plane surfaces forming the lozenge or diamond shape at the inner end of the crank-arm are similarly tapered from the inner toward the outer end of the arm, and said oblique plane surfaces intersect and are bounded by the four tapering front, rear, and side 45 surfaces mentioned, so that the margins of each intermediate oblique surface are coincident with the margins of the adjacent front rear, and side surfaces, and said intermediate oblique surfaces are widest at the crank end 50 of the arm and taper toward the outer end thereof, where the outer margins of each of said oblique surfaces intersect each other and merge into the meeting edges of the adjacent front, rear, and side surfaces. The oblique 55 plane surfaces forming the outer faces of the arm at the inner end thereof extend to and intersect the convexly-rounded surface, which forms a continuation of the cylindric surface of the shaft. The oblique surfaces forming 60 the inner faces of the arm are of less length than the outer oblique surfaces and extend to and terminate in two flat side surfaces adjacent to the sprocket-wheel flange. At the intersection of said flat surfaces and oblique 65 surfaces are inwardly-curved or concave surfaces, as shown in Fig. 2, into which the said intermediate oblique surfaces are merged.

I claim as my invention—

The design for a crank-arm and sprocket-wheel flange for velocipedes, substantially as herein shown and described.

Signed at Chicago, Cook county, Illinois, on the 3d day of January, 1900.

ALBERT M. PRICE.

In presence of—

C. W. HILLS,
GERTRUDE BRYCE.
